IRONING CORD HOLDER

William M. Fish, St. Petersburg, Fla.

Application March 22, 1937, Serial No. 132,400

1 Claim. (Cl. 248—51)

This invention relates to ironing cord holders and has for an object to provide a holder including a stationary hook and a traveling hook upon which the cord rests at points between the electric outlet and the smoothing iron.

A further object is to provide a holder for the traveling hook adapted to be collapsed flat against a door, wall, or other support, so as to be out of the way and inconspicuous when not in use.

10 A further object is to provide a device of this character which will be formed of a few strong simple and durable parts, which will be inexpensive to manufacture, and which will not easily get out of order.

15 With the above and other objects in view the invention consists of certain novel details of construction and combinations of parts herein-after fully described and claimed, it being understood that various modifications may be resorted 20 to within the scope of the appended claim without departing from the spirit or sacrificing any of the advantages of the invention.

In the accompanying drawing forming part of this specification,

25 Figure 1 is a perspective view of an ironing cord holder constructed in accordance with the invention.

Figure 2 is a front elevation of the holder in collapsed position.

30 Figure 3 is a front elevation of the traveling hook showing the V-shaped bight of the hook for clamping the cord.

35 Referring now to the drawing in which like characters of reference designate similar parts in the various views, 10 designates a substantially V-shaped resilient hook which is fixed at one end by a screw 11 or other connector to a support such as a door frame 12 near an electric outlet 13.

A substantially V-shaped holder 14 is provided, 40 one leg of the holder having the end 15 directed at about an angle of 90 degrees to the leg and detachably engaged in an eye 16 having an integral flange 17 which is rigidly secured to a door 18, or other suitable support by a screw 19.

45 The other leg of the holder terminates in a hook 20 which is supported in an eye 21 that is superposed above and is in alignment with the eye 16. The eye 21 is provided with a flange 22 which is pivotally secured to the door 18 by a 50 screw 23, or other connector so that the eye may be swung to extend horizontally.

The holder 14 is preferably formed of spring wire and in operative position one leg 24 of the holder extends horizontally outward from the door 18 while the other leg 25 extends obliquely upward. In release position the leg 24 of the 5 holder may be disengaged from the eye 16 whereupon the holder may be rotated on the pivot 23 to lie flat against the door 18. Thereupon the bent extremity 15 of the leg 24 may be inserted in a stationary horizontally extending eye 26 having 10 a flange 27 secured stationary to the door by a screw 28 or other connector, as best shown in Figure 2.

A traveling hook 29 formed of resilient material and of substantially V-shape in cross section 15 is provided with a fork 30 between the branches of which a grooved pulley 31 is rotatably mounted on a shaft 32. The pulley rides on the track formed by the horizontally extending leg 24 of the holder during the ironing operation and is 20 received in the bight of the holder at the junction of the legs of the holder when the device is not in use. The ironing cord 33 is supported in the stationary hook 10 and in the traveling hook 29 between the electric outlet 13 and the smoothing iron 34 and during the ironing operation the traveling hook may freely move along the horizontally extending leg 24 of the holder to accommodate the length of the cord to the movements 25 30 of the smoothing iron.

From the above description it is thought that the construction and operation of the invention will be fully understood without further explanation.

35 What is claimed is:

An ironing cord holder comprising a stationary hook, a traveling hook, said hooks being adapted to support an ironing cord between an electric outlet and a smoothing iron, a pair of superposed 40 vertically aligned eyes, the uppermost eye being pivotally mounted, a substantially V-shape holder for the traveling hook having the ends swivelly engaged in said eyes, and a stationary eye disposed laterally of the pivoted eye and adapted 45 to receive one leg of the holder when the holder is swung on the pivoted eye of the pivot and hold the holder in release position against a supporting wall.
